D. 343,362 1/1994 Soren et al. D10/65

Primary Examiner—Antoine Duval Davis
Attorney, Agent, or Firm—Pierce Atwood; Chris A. Caseiro[57] **CLAIM**

The ornamental design for a global positioning system receiver with clamshell shape, as shown.

DESCRIPTION

FIG. 1 is a front plan view of a global positioning system

1 Claim, 3 Drawing Sheets

receiver with clamshell housing, showing the design with appropriate shading;

FIG. 2 is a left side elevation view of the housing shown in FIG. 1;

FIG. 3 is a back plan view of the housing shown in FIG. 1; FIG. 4 is a right side elevation view of the housing shown in FIG. 1;

FIG. 5 is a top elevation view of the housing shown in FIG. 1;

FIG. 6 is a bottom elevation view of the housing shown in FIG. 1;

FIG. 7 is a front plan view of a global positioning system receiver with clamshell housing, showing the design without shading and with dashed lines to indicate those features of the design that are alternative embodiments;

FIG. 8 is a left side elevation view of the housing shown in FIG. 7;

FIG. 9 is a back plan view of the housing shown in FIG. 7; FIG. 10 is a right side elevation view of the housing shown in FIG. 7;

FIG. 11 is a top elevation view of the housing shown in FIG. 7;

FIG. 12 is a bottom elevation view of the housing shown in FIG. 7; and,

FIG. 13 is a perspective view of the housing shown in FIG. 7.

The broken lines are shown for illustrative purposes only and form no part of the claimed design.
